Water tube connection for rock drills, which includes a front head secured to a cylinder, the cylinder having a longitudinal slot or recess extending from the front end to the rear end, the slot being provided with a gasket and a tapered plug, the slot being closed at the rear end by a closure plug and at the front end by a front head secured to the cylinder.

UNITED STATES PATENT OFFICE

GEORGE H. FUEHRER, OF PHILLIPSBURG, NEW JERSEY, ASSIGNOR TO INGERSOIL-RAND COMPANY, OF JERSEY CITY, NEW JERSEY, A CORPORATION OF NEW JERSEY

WATER TUBE CONNECTION

Application filed September 24, 1931. Serial No. 564,773.

This invention relates to rock drills, but more particularly to a water tube connection for that type of rock drills in which water is supplied to a hollow working implement 5 for cleansing the drill hole.

One object of the invention is to assure an adequate seal between the cleansing fluid conveying element and the percussive element of the rock drill.

Another object is to facilitate the operation of removing and inserting the cleansing fluid conveying elements from and into the rock drill.

Still another object is to simplify the construction and to facilitate the assembly of devices of this character.

Other objects will be in part obvious and in part pointed out hereinafter.

In the drawing accompanying this specification and in which similar reference characters refer to similar parts,

Figure 1 is an elevation partly in section of a rock drill equipped with a water tube connection constructed in accordance with the practice of the invention,

Figure 2 is an enlarged sectional elevation of the water tube connection,

Figures 3 and 4 are sectional elevations of details, and

Figure 5 is a transverse view taken through Figure 2 on the line 5-5 looking in the direction indicated by the arrows.

Referring more particularly to the drawing, the rock drill wherein the invention is embodied is designated in general by A and comprises a cylinder B and a hammer piston in the cylinder and only the extreme forward end C of which is shown. The rock drill A may be provided with suitable pressure fluid distributing mechanism to effect the distribution of pressure fluid to the cylinder B for actuating the piston and such mechanism, of which only a valve chest D is indicated, may be conveniently arranged 45 on the side of the cylinder B.

The cylinder B is provided with the usual back and front heads E and F, respectively, which may be secured to the cylinder by means of the side bolts G only a portion of 50 one of which is indicated.

As is customary, the front head F affords a housing for chuck mechanism designated in general by H and being adapted to accommodate a working implement such as a hollow drill steel J which extends with its rear end into a cavity K in the chuck mechanism H to receive the blows of the hammer piston which in the present instance are transmitted to the drill steel by an anvil block L in the chuck mechanism H.

The rock drill A is illustrated as being of the type equipped with means for supplying cleansing fluid to the hollow drill steel J whereby it is conveyed into the drill hole to wash or flush the cuttings therefrom so that a clean working face may be at all times presented to the cutting bit of the working implement. The drill A is accordingly provided with a water tube O which extends through an aperture P in the back head and through the cylinder B and the chuck mechanism H and with its front end Q into the drill steel J.

In the rear end of the back head E is a recess R through which the rear end of the tube O extends and into which the rear of the aperture P opens. The tube O is preferably provided with an external flange or enlargement S to seat upon the bottom of the recess R and thus definitely limit the distance that the tube O may extend into the drill steel J.

A closure is provided for the recess R in the form of a plug T having a head U which may be conveniently shaped for the accommodation of a wrench or similar implement employed for threading the plug T into the recess R. Preferably a gasket V is interposed between the head U and the rear end of the back head to seal the rear end of the recess R.

The portion or extension W of the plug T which lies within the recess R may be somewhat reduced in diameter and is provided with a passage X into which the rear end of the tube O extends. The passage X may, as indicated, increase progressively in cross sectional area in the direction of the rear end or roof Y of the passage X to assure an abundant supply of cleansing fluid.

to the tube. Such cleansing fluid is conveyed to the passage X by a passage or passages Z in the plug T and which passages open at their outer ends into an annular groove b in the outer surface of the plug T.

The cleansing fluid may be supplied to the groove b in any suitable and convenient manner, as for instance by a passage c in the back head E and which communicates at one end with the groove b and with its other end with a connection d leading from a suitable source of supply.

In order to prevent the leakage of water from the recess R into the aperture P, and consequently into the cylinder B, a packing member e is disposed in the recess R to encircle the tube O and seat upon the bottom of the recess R. The packing member e is preferably of smaller diameter than the recess and is disposed within a cup-like receptacle f through which the tube O also extends. On the receptacle f is a rear bevelled surface g to seat against a correspondingly bevelled surface h on the front end of the plug T for retaining the receptacle in coaxial alignment with the plug and to prevent tilting of the one with respect to the other. On the same end of the receptacle f and preferably adjacent the inner bounding edge of the bevelled surface g is an annular flange j which extends into a coniform annular recess k in the front or inner end of the plug T and encircling the passage X.

The annular recess k diverges from the front or open end thereof so that when the flange j lies therein the receptacle f will be suitably secured to the plug T by the outer surface of the flange j which engages the outer walls of the groove k. The groove k and the flange j are, however, so proportioned that when these elements are in engagement with each other the plug T and the receptacle f are capable of freely rotating with respect to each other.

By means of the foregoing described construction leakage of water from the recess R into the cylinder B will be entirely eliminated. The packing member e will not be unduly distorted and for that reason will remain fit for long periods of use. By connecting the plug T and the receptacle f in the manner described these elements, as well as the packing member e, may be conveniently removed from the recess R as a unit to afford access to the tube O.

The manner in which the receptacle f and the plug T may be connected together is as follows: The receptacle f, as illustrated in Figure 4, is originally constructed with a cylindrical flange j. In securing the receptacle and the plug together the outer end of the flange j is seated in the open end of the groove k. A blow, as by means of a hammer, may then be delivered to the re-

ceptacle which, of course, consists of suitable malleable material. Upon the application of a blow to the receptacle f the inner surface of the flange j will contact with the inner end of the wall k and the flange j will thus be distorted, that is, the flange j becomes flared in the direction of its outer or free end to conform to the angularity of the groove k. In this manner the receptacle will be permanently attached to the plug T and in such wise that the receptacle f is capable of free rotation with respect to the plug T. This is desirable for the reason that in threading the plug T into the recess R or unthreading it therefrom the receptacle f may remain stationary in the bottom of the recess R and the packing member e will be protected against chafing or undue wear such as might otherwise occur thereto were a metallic element or elements of harder substance rotated thereon.

I claim:

In a rock drill, the combination of a cylinder and a back head therefor having a recess, a tube in the cylinder and the back head and extending into the recess, a plug in the recess having a passage to receive the end of the tube and for conveying cleansing fluid to the tube, said plug having an annular groove therein, a bevelled surface on the plug, a packing member encircling the tube and seating against the end wall of the recess to prevent leakage of water into the cylinder, a receptacle to receive the packing member and to retain the packing member in sealing relation with the tube, a flange on the receptacle extending into the groove and being in engagement with the wall thereof for securing the receptacle to the plug, and a bevelled surface on the receptacle seating against the first mentioned bevelled surface to retain the receptacle in coaxial alignment with the plug.

In testimony whereof I have signed this specification.

GEORGE H. FUEHRER.
